Attorneys.

UNITED STATES PATENT OFFICE.

CHARLES P. REID, OF LOUISVILLE, KENTUCKY.

BROOM.

1,313,206.

Specification of Letters Patent. Patented Aug. 12, 1919.

Application filed April 2, 1919. Serial No. 286,894.

To all whom it may concern:

Be it known that I, CHARLES P. REID, a citizen of the United States, residing at Louisville, in the county of Jefferson and State of Kentucky, have invented certain new and useful Improvements in Brooms; and I do hereby declare the following to be a full, clear, and exact description of the invention, such as will enable others skilled in the art to which it appertains to make and use the same:

My invention relates to improvements in brooms of that class in which the broom holder and the broom head are detachably connected together so that the broom holder and handle connected to the same may be used indefinitely; while the broom heads may be replaced whenever desired, as when the broom becomes worn out, or when it is desired to change the broom head for any other reason, such, for instance, as to shift a dry broom head in place of a wet one, or a clean broom head in place of a soiled one, dependent upon the work required of the broom.

The main purpose of this construction is primarily to save the expense in the manufacture and use of brooms, and in order to meet the commercial demand it is necessary not only that the broom holder shall be of a cheap, simple and comparatively rugged construction, so that it is not likely to get out of order; but also so that the parts may be readily assembled without the necessity of having any expert mechanical knowledge.

It is especially desirable that the broom head and broom holder may be put together and separated by the most ignorant class of servants, such as inferior kitchen help or the like.

My invention is intended to provide a broom of this character in which both the broom and the broom holder may be cheaply constructed, and may be efficient in use, and in which the two may be readily, quickly and conveniently assembled and disassembled when desired, and in which the broom holder may be used indefinitely without getting out

of order, and in which, if desired, the broom head may be made of a cheap quality of broom straw.

My invention will be more fully understood after reference to the accompanying drawings, in which like parts are indicated by similar reference symbols throughout the several views, and in which:—

Figure 1 is a front view of the complete broom, the handle being broken away.

Fig. 2 shows a side elevation of the broom shown in Fig. 1, with the hinged jaw shown in full lines in the holding position and in dotted lines in the open position.

Fig. 3 shows the broom head removed from the broom holder, parts being broken away.

Fig. 4 shows a section through the broom holder and handle along the lines 4—4 of Fig. 1, and looking in the direction of the arrows, the broom head being removed; and

Fig. 5 shows a section through the broom holder along the lines 5—5 of Fig. 1, the broom head being removed.

A represents the broom head which may be made of the usual straw from broom corn, but I prefer to use the shorter and cheaper straw for the body of the broom head, using the stems *a* for the upper part of the broom head which is held in the holder, as will be hereinafter described.

The broom straw is formed in bundles of the desired shape, and these are sewed together as at B, B' and B''. The top of the broom head is preferably provided with a cap C, which may be of metal, canvas, or other suitable material, fitted or cemented to the broom head as shown in Fig. 3.

Extending across the body of the broom head, preferably between seams B' and B'', I provide a stiffening bar D, preferably dentated at one or more edges as at *d*, so as to prevent it from slipping longitudinally in the broom head, and the ends *d'* of this bar project beyond the edges of the broom head and terminate in the heads *d''*, for purposes hereinafter to be described.

E represents the broom handle which is

permanently connected to the frame F of the broom holder, as by means of the screw G passing through the ferrule e at the lower end of the broom handle, and engaging in 5 the handle, and also by means of the bolt G' held in place by the nut g'.

This frame F is preferably made of a single piece of sheet metal, stamped to form the side strips f connected together by the cross webs f', f² and f³. The cross web f' is 10 preferably bent downwardly, as shown at f⁴, to serve as a guide for the head of the broom. The side strips f of the frame F are provided with outwardly projecting lugs f⁶, 15 and the cross web f³ is provided with inwardly projecting teeth f⁵ to engage in the broom head; and the side strips f are also perforated, as at f⁷, to permit the insertion of the ends of the stiffening bar D. 20 The jaw H is hinged as at h to the frame F, and is cut away as at h⁰ so that the head of the jaw may project inside of the side strips f, and the outer flanges h' of the jaw may swing outside of the strips f, and the 25 back h² of the jaw will bring up against these strips f when the jaw is in the closed position as shown in Figs. 1, 2 and 4.

The back of the jaw is provided with inwardly projecting teeth h³ adapted to engage in the broom head on the face opposite to the teeth f⁵.

The jaw H is also provided with perforations h⁴ to permit the insertion of the ends of the stiffening bar D; and also with perforations h⁵ to permit the snapping into the same of the lugs f⁶ of the main frame.

In practice, the frame holder, comprising the handle E, the frame F and the jaw H, 40 constitutes one member of the completed broom, and the broom head constitutes the other member, and to assemble these two parts all that is required is to swing the jaw H to the open position shown in dotted lines in Fig. 2, insert the broom head in the recess 45 in front of the guide rib f⁴, and then insert the ends of the stiffening bar D in the holes f⁷ in the frame F. Now swing the jaw down to the closed position, springing out the sides so as to permit the ends d² of the 50 stiffening bar D to snap into the holes h⁴, and also permitting the teeth f⁵ of the main frame to snap into the holes h⁵ in the jaw. The broom head will now remain firmly 55 locked in the holder, and the broom may be used until the broom head is worn out, if desired.

In order to remove the broom head from the holder, it will be sufficient to merely 60 spring out the sides h' of the jaw, to release the lugs f⁶, and the ends d² of the bar D, swing the jaw clear and then release the ends d² of the bar D from engagement with

the holes f⁷, and the broom head may be removed bodily from the holder. The latter is then ready for the insertion of a new 65 broom head.

It will be seen that the lugs f⁶ and the recesses h⁵ will serve to keep the jaw locked in the holder if desired, when there is no broom head mounted in the holder. Thus, 70 as a matter of convenience in shipping the holder separate from the broom heads, there is no danger of the jaw becoming loose and being bent out of shape.

It will be seen that with the herein described construction very light metal parts 75 may be used, which at the same time are not likely to become so bent as to be inoperative.

It will be noted that by having the stems a of the tufts of broom corn project up into 80 the holder, a common and cheap quality of broom corn having short straw may be used in making the broom heads, without impairing the efficiency or durability of the broom.

It will be seen that the assembling and 85 disassembling of the parts will not require either skill or intelligence, and that the broom is practically "fool proof."

It will be obvious that various modifications in the construction, combination and arrangement of the parts may be made without departing from the spirit of my invention; and I do not desire to limit the invention to such details except as particularly 90 pointed out in the claims.

Having thus described my invention what I claim and desire to secure by Letters Patent of the United States is:—

1. In a broom the combination with a broom-head having a stiffening bar mounted 100 transversely therein, the ends of said bar being reduced and protruding beyond the edges of the broom-head, of a metallic holder for said broom-head comprising a frame made of sheet metal adapted to receive the upper portion of said broom-head, a jaw hinged to said frame, the said frame and jaw being provided with perforations to engage the protruding ends of said stiffening bar, and a handle secured to said 110 frame, substantially as described.

2. In a broom the combination with a broom-head having a stiffening bar mounted transversely therein, the ends of said bar being reduced and protruding beyond the 115 edges of the broom-head, of a metallic holder for said broom-head comprising a frame made of sheet metal adapted to receive the upper portion of said broom-head, a jaw hinged to said frame, the sides of said frame being provided with protruding locking lugs adapted to snap into recesses provided in the sides of said jaw, the said frame and jaw being also provided with

perforations to engage the protruding ends of said stiffening bar, and a handle secured to said frame, substantially as described.

- 5 3. In a broom provided with a detachable broom-head, a metallic holder for the broom-head comprising a locking frame made of sheet metal having a socket at its upper end adapted to receive the upper portion of the

broom-head, and provided with side strips having lugs projecting from said side strips, 10 a jaw hinged to said frame having flanged sides provided with notches adapted to engage said lugs, and a handle secured to said frame, substantially as described.

CHARLES P. REID.
